[57] CLAIM

The ornamental design for a moated pet feeder, as shown and described.

DESCRIPTION

FIG. 1 is an exploded perspective view of a moated pet feeder showing our new design;

FIG. 2 is a top plan view;

FIG. 3 is a bottom plan view;

FIG. 4 is a right side elevational view, the left side elevational view being a mirror image thereof;

FIG. 5 is a front elevational view; the rear elevational view being a mirror image thereof;

FIG. 6 is a cross-sectional view provided to show the design detail of the bowl locking ports, one with a bowl in place and one without;

FIG. 7 is a top plan view with both bowls removed to reveal the design; detail of the empty unit.

The dashed lines on the sides of FIGS. 1, 2, 3 and 7 are pieces which punch-out to accommodate ground stakes.

FIG. 7
